UNITED STATES PATENT OFFICE.

WILLIAM H. MINER, OF CHICAGO, ILLINOIS

DRAW-BAR AND YOKE CONNECTION FOR RAILWAY DRAFT-RIGGING.

1,073,275.

Specification of Letters Patent. Patented Sept. 16, 1913.

Application filed December 30, 1910. Serial No. 600,170.

To all whom it may concern:

Be it known that I, WILLIAM H. MINER, a citizen of the United States, residing in Chicago, in the county of Cook and State of Illinois, have invented a new and useful Improvement in Draw-Bar and Yoke Connections for Railway Draft-Rigging, of which the following is a specification.

My invention relates to improvements in car coupler draw-bar and yoke connections.

Heretofore, great difficulty has been experienced in draw-bar and yoke connections generally in use from shearing of the two rivets which extend through the draw-bar and yoke under the heavy strains, shocks and blows to which railway draft rigging is subjected.

The object of my invention is to provide a draw-bar and yoke connection which will be very much stronger than the two rivets heretofore employed, and which at the same time will enable the yoke and draw-bar to be connected by a pair of rivets when occasion may require for repairs or other purposes.

My invention consists in the means employed to practically accomplish this object or result as herein shown and described and more particularly specified in the claims.

In the accompanying drawing forming a part of this specification, Figure 1 is a plan view of a draw-bar and yoke connection embodying one form of my invention. Fig. 2 is a side elevation, partly in central, vertical section on line 2—2 of Fig. 1. Fig. 3 is a detail plan view showing a preferred means for securing the key in place. Fig. 4 is a detail section on line 4—4 of Fig. 3. Fig. 5 is a detail section on line 5—5 of Fig. 4. Fig. 6 is a detail plan view, showing the 40 filler block which is interposed in the key slot of the draw-bar when it is desired to connect the same by rivets. Fig. 7 is a horizontal section showing the preferred form of the key slot in the draw-bar and of the 45 filler block recess. Fig. 8 is a detail section on line 8—8 of Fig. 7. Fig. 9 is a detail elevation of the filler block employed in the construction shown in Figs. 7 and 8 and Fig. 10 is a detail plan view of same.

In the drawing, 1 represents the draw-bar and 2 the draft yoke. The draw-bar is preferably furnished with the usual shoulders 3 for engagement with the gibs 4 at the for-

ward ends of the two limbs of the draft yoke, the draw-bar preferably having transverse grooves 5 in its upper and lower faces to receive the gibs 4 of the draft yoke and thus affording further abutment shoulders 6 on the draw-bar for engagement with the draft yoke gibs.

The draw-bar is provided with an upright longitudinal slot 7, having semi-circular end walls 8, the transverse width of the slot 7 being the diameter of the customary rivets employed in the regular Master Car Builders' construction, and the length of the slot 7 corresponding to the spacing of the rivet holes in the customary or standard Master Car Builders' construction. The draft yoke 2 in like manner is furnished at its front ends with an upright, longitudinal slot 9 having semi-circular front and rear walls 10, 11 and conforming in shape and size to the slot 7 in the draw-bar.

12 is a connecting key having a head 13 at its upper end and semi-circular curved front and rear walls 14, 15 adapted to snugly fit the upright slots in the draw-bar and yoke. A washer 16 is provided at the lower end of the key and a fastener 17, which is inserted through an opening in the lower end of the key and which serves to hold the key in place. Filler blocks 18, having convexly curved front and rear walls 19, 20 are adapted to fit in the slot of the draw-bar when the key connection is not employed, and rivets 21 are employed with a rivet-hole yoke of the standard Master Car Builders' present construction for connecting the draw-bar and draft yoke.

In the construction shown in Figs. 3, 4 and 5, a wedge 22 is employed as the fastener for securing the key 12 in position, the key in this construction having a slot 23 with an inclined face 24 for engagement with the inclined face 25 of the wedge. The wedge is secured in position by a locking device 26, the key having a series of holes 27 to receive the locking device 26.

In Figs. 7, 8, 9 and 10, which illustrate the preferred construction of filler block, the filler block is provided with lugs 28 on its upright longitudinal faces which fit in short, transverse recesses or grooves 29 in the upright side walls of the key slot 7, the lugs 28 serving to hold the filler block in

place and giving the same anchorage in the draw-bar independent of the rivets. The filler block thus serves as an additional connection between the draw-bar and yoke 5 in resisting buffing and pulling strains.

I claim:—

1. A draw-bar and yoke connection comprising, in combination: a draw-bar provided with an upright slot therethrough of 10 a width equal to the diameter of a standard rivet and having semi-circular curved front and rear walls, the centers of curvature of said front and rear walls of the draw-bar slot being spaced apart a distance 15 equal to the distance between centers of a pair of standardly spaced connecting rivets; a draft yoke, the arms of which are provided with perforations in alinement with the slot of the draw bar; means for connecting said draw-bar and draft yoke, said 20 means including a pair of connecting rivets extending through the draw-bar and yoke and a filler block; and coöperating means on the draw-bar and filler block for anchor-

ing the latter in position, substantially as 25 specified.

2. The combination with a draw-bar and draft yoke both provided with upright, longitudinally extending slots having semi-circular front and rear walls spaced apart a 30 distance corresponding to the distance between a pair of standardly spaced connecting rivets, a filler block having concavely curved front and rear walls, fitting in said slots of the draw-bar and yoke, and a pair 35 of connecting rivets extending through the draw-bar and yoke and engaging the curved front and rear walls of said slots and the concavely curved front and rear walls of said filler block, said filler block having 40 anchoring lugs on its upright sides and the draw-bar having recesses to receive said anchoring lugs, substantially as specified.

WILLIAM H. MINER.
